UNITED STATES PATENT OFFICE.

CHARLES E. JONES, OF CHICAGO, ILLINOIS, ASSIGNOR TO METAL ARTS & CRAFTS CO.,
OF CHICAGO, ILLINOIS, A CORPORATION OF ILLINOIS.

DESIGN FOR A FANCY LINK FOR CENTER OF ROD-SPINDLES AND PENDANT LIGHTS.

49,031.

Specification for Design.

Patented May 9, 1916.

Application filed March 28, 1916. Serial No. 87,365. Term of patent 3½ years.

To all whom it may concern:

Be it known that I, CHARLES E. JONES, a citizen of the United States, residing at Chicago, in the county of Cook and State of Illinois, have invented a new, original, and ornamental Design for a Fancy Link for Center of Rod-Spindles and Pendant Lights, of which the following is a specification, reference being had to the accompanying drawing, forming a part thereof.

The figure is a front view of a fancy link for center of rod spindles and pendant lights, showing my new design.

I claim:

The ornamental design for a fancy link for center of rod spindles and pendant lights, as shown.

CHARLES E. JONES.
